CLAIM

The ornamental design for a surgical cannula, substantially as shown and described.

DESCRIPTION

FIG. 1 is a perspective view of a surgical cannula in accordance with the present invention;

FIG. 2 is a front view thereof;

FIG. 3 is a right side view thereof;

FIG. 4 is a rear view thereof;

FIG. 5 is a left side view thereof;

FIG. 6 is a top elevational view thereof; and,

FIG. 7 is a bottom elevational view thereof.

The broken lines in the drawings illustrate portions of the surgical cannula and form no part of the claimed design.

1 Claim, 7 Drawing Sheets
